UNITED STATES PATENT OFFICE.

JOHN RUTHERFORD KIRKSEY, OF DYSARTVILLE, NORTH CAROLINA.

CAR-COUPING.

SPECIFICATION forming part of Letters Patent No. 290,243, dated December 18, 1883.

Application filed April 21, 1883. (No model.)

To all whom it may concern:

Be it known that I, JOHN RUTHERFORD KIRKSEY, a citizen of the United States, residing at Dysartville, in the county of McDowell and State of North Carolina, have invented certain new and useful Improvements in Car-Couplers, of which the following is a specification, reference being had therein to the accompanying drawings.

10 My invention relates to certain details of construction in an automatic car-coupler, which I will now proceed to describe, and which will afterward be distinctly pointed out in the claims.

15 In the drawings which form a part of this specification, Figure 1 is a vertical section of my improved coupler, represented as when in use, one on each of the adjacent ends of the car, showing the pivoted latch in both open and closed positions. Fig. 2 is an inverted plan view. Fig. 3 is a top plan view, with latch removed, and Fig. 4 is a perspective view of the coupling-link or clevis.

20 The device is substantially in the form of a box or casing, with recessed top and bottom portions, leaving a central wall or partition, the latter being perforated or provided with suitable apertures for the levers or rods, which are used to operate the latch and release the link or clevis.

25 The figures 1 1 represent the end walls, and 2 2 the side walls of the casing. The top of the side walls form what may be called "flanges," which project above the middle portion, 12, and these flanged parts are beveled or made flaring at their front ends, as shown in Fig. 3. Between these upwardly-projecting parts 2 2 is pivoted the latch 3, which is of the same general form as the portion of the casing in 30 the side of the vertical flanges or walls 2 2, and having shoulders at the front end corresponding with the beveled or flaring parts of the casing. The latch is provided with a lug on its under side, which, resting upon the middle or partition wall, 12, acts as a fulcrum in the operation of opening and closing it, and it is pivoted just above this lug by means of a pin, 13, which is passed through the sides of the frame or casing and transversely through 35 the latch.

40 At the front end of the coupler, on top of

the middle part, 12, and immediately adjacent to the front aperture therethrough, I provide a lug, b, to engage the link or clevis 4.

Through the rear perforation or aperture, 55 and through a corresponding hole in the rear end of the latch, is the operating rod or lever, 7. This operating-rod is pivoted at its lower end to a substantially horizontal lever, 5, which lies in the bottom recess in the casing, 60 and which is pivoted thereto by a pin, 10, which is passed transversely through it and through the sides of the casing. This lever 5 has also pivoted to it at the front end a vertical lever, c, which passes upward through 65 the hole in the front part of the wall 12, and is designed to release the link or clevis from engagement with the lug b.

70 The operating-lever is provided with a nut, 6, which is loose thereon, so as to allow of limited vertical movement; but it is held from being pushed too far upon the rod either by means of a pin or toggle passed through a hole in the rod or by means of a suitable threaded nut. The lever 7 is also surrounded by a spiral spring, a, one end of which rests against the under side of the latch, and the other end rests against the top of the middle wall, 12, or in a recess formed therein. The clevis or link is preferably made with a central transverse 75 bar, and its ends are wedge-shaped, as clearly shown in Fig. 4, so that it will couple the more readily. The nut 6 may also be beveled at its lower end, as shown, although this is not absolutely necessary. The coupler is attached 80 to the frame-work or buffer of the car by means of the arm 8.

75 When the coupler is designed for use on a passenger-car, it will be made with the operating-lever short, or substantially as shown in 90 the drawings, and will be operated by the foot, and a foot piece or rest may be provided on top of the rod or lever. For freight-cars, I prefer either to extend the lever 7 to the top of the car, or to attach to it a transverse arm 95 or lever to extend to the side of the car, from which points it may be operated, so that in any event it is unnecessary to go between the cars to uncouple them.

85 The operation of my invention is as follows, 100 viz: The coupling-link or clevis is always attached to one of the coupling-boxes, and the

box on the adjacent car is without the link. When the cars are run together, the wedge-shaped end of the coupling-link raises the correspondingly wedge-shaped end of the latch, 5 and the link engages with the lug *b* and is held in engagement, or, rather, prevented from uncoupling by means of the spring *a*, which holds the latch down over it, and it will be apparent that the parts will be coupled whether the link 10 is in a straight line or not. To uncouple, the lever 7 is pressed downward against the tension of the spring, and this pressure raises the front end of the pivoted lever 5 and the vertical lever *c*, which raises the end of the link or clevis 15 above the projection or lug *b* and allows it to escape and the car to be uncoupled.

Having thus fully described my invention, what I claim as new, and desire to secure by Letters Patent, is—

20 1. A car-coupler comprising the box or casing with the top and bottom recessed portions,

the pivoted top latch, the operating mechanism consisting of the vertical rod 7, provided with a nut and spring, the transverse arm or lever 5, and the vertical rod or arm *c*, the lug 25 *b*, and a suitable clevis or coupling-link, substantially as set forth.

2. A car-coupler consisting of the box or casing with recessed top and bottom, the latch pivoted in the top recess, the uncoupling devices comprising the rod or arm 7, provided with a spring and nut, the transverse arm 5, and the vertical rod *c*, the lug *b*, and the coupling-link with wedge-shaped ends, substantially as set forth.

35 In testimony whereof I affix my signature in presence of two witnesses.

JOHN RUTHERFORD KIRKSEY.
